HUB CONSTRUCTION FOR VARIABLE PITCH PROPELLERS OR THE LIKE

Robert E. B. Sharp, York, Pa., assignor to S. Morgan Smith Company, York, Pa., a corporation of Pennsylvania

Application January 14, 1947, Serial No. 721,944

5 Claims. (Cl. 170—160.23)

1

This invention relates to rotors having adjustable blades and more specifically to the construction of the hubs thereof.

An important object of the invention is the provision, in a construction of this type, of an arrangement whereby the bearings in which the adjustable blades are mounted and the operating connections by which adjustment of the blade position is obtained, can be fully and constantly lubricated.

Another and more specific object of the invention is the provision of a structure of this character wherein a hub, having internal bearings mounting a plurality of rotatability, adjustable blades projecting therefrom, is provided with a sealing means between the rotating blades and hub shell of such character that the hub structure is maintained as a sealed container without regard to the positional adjustment of the blades.

A further and still more specific object of the invention is the provision means for maintaining within a hub of this character a pressure substantially equal to that to which the sealing means between the hub and blades is externally subjected.

These and other objects are obtained by the construction showed in the accompanying drawings, wherein, for the purpose of illustration, I have shown my invention as applied to a ship propeller hub, and wherein:

Figure 1 is a fragmentary longitudinal section through a propeller hub construction in accordance with my invention,

Figure 2 is a fragmentary sectional view taken on line 2—2 of Figure 1.

Figure 3 is a section similar to that of Figure 1 showing the operating shaft moved further into the hub, and

Figure 4 is a section on line 4—4 of Figure 1.

Referring more particularly to the drawings, the numeral 10 designates a shaft having a flange 11 by means of which it is attached as at 12 to hub 13, said hub mounting radial blades 14, only one of which is herein illustrated. The hub 13 comprises a shell 15, having an upper wall 16 engaged by securing the elements 12, sockets 17, for the reception of the shanks 18 of blades 14, and a rear end closure 19, more particularly described hereinafter.

Shaft 16 is hollow and has directed therethrough means for rotating blades 14. In the present instance, the rotating means comprises a reciprocating shaft 20, having bearing in the shell at 21 and having secured thereto a collar

2

22 including projecting arms 23 for connection to stems 18. Stems 18 are mounted in spaced bearings 24 and 25, supported by shell 15, and an extended tubular portion of the upper wall 13 respectively, and in the present instance have secured thereto, intermediate bearings 24 and 25, collars 27 linked at 28 to arms 23, whereby reciprocation of shaft 20 will result in rotative oscillation of the stems 18 and consequently of blades 14. It is to be understood that this means of oscillation of the blades is purely illustrative and may be substituted for by any of the well-known means through which adjustable blades of this character are manipulated.

In accordance with my invention, the hubs of blades 14 and the shell surrounding the hubs, are connected by diaphragms 29, which may be constructed of any suitable substance which is 20 resistant to an internal lubricant and the external fluid, and which is not only resilient but elastic to withstand distortion as hereinafter explained. This diaphragm is sealed by clamping means 30 at its periphery to shell 15 and by 25 clamping means 31 at its inner diameter to the hub of blade 14. Since the blade 14 is rotatably adjustable, the diaphragm is of material sufficiently elastic to withstand distortion between its normal operating position A shown in Figure 30 2, and its maximum adjustment positions, indicated at B and C respectively, the diaphragm 29 being undistorted at the medial or operating position A for obvious reasons.

The hub shell, and more specifically the end 35 cap of closure 19 thereon, includes an expansible chamber 32, internal wall of which is in the form of a flexible diaphragm 33. The interior of chamber 32 is connected through a suitable conduit 34 with the exterior of the hub at a point 40 essentially in a plane including the axes of blade shanks 18. It is recognized that in the case of rotors having adjustable blades such as ships' propellers, hydraulic turbine runners, pump impellers, or where such a rotor operates in any 45 fluid, the external pressure at the up-stream end of the hub exceeds that of the rear or down-stream end. By connecting the expansible chamber 32 to the exterior of the hub at a point where the average external pressure exists, the difference in pressure between the exterior and interior of the hub is minimized, with the result that diaphragms 29 are not subjective to material pressure differences therein at the interior and exterior surfaces, with the increasing reduction in wear which would occur where these pres-

sure differences cause displacement of the diaphragm to an extent causing contact thereof with one or another of the relative movable surfaces between which they are disposed.

To seal the chamber within which the hub stmes are mounted, I provide a seal between the upper end wall 16 of hub 13 and the reciprocatory shaft 20. At the present this seal comprises a collar 35 which may be integral with or secured to shaft 20 and a diaphragm 36 sealed to this collar and to the upper end wall 16 of shell 15.

It is furthermore pointed out that in a construction of this sort where the hub is in a form of a sealed chamber and a reciprocating control for pitch variation is utilized, the capacity of this chamber will vary in accordance with the position of operating shaft 20. Expandible chamber 32 serves not only as a means for equalizing internal and external pressures as outlined above, but likewise as a means for compensating for this variation of internal capacity and to eliminate strains which would otherwise be placed upon diaphragms 29 and 36. All of the diaphragms 29, 33 and 36 are provided with circumferentially extending corrugations or are otherwise designed to permit the desired deflection. In the case of diaphragms 33 and 36, the purpose of such corrugations will be readily understood, and in the case of diaphragms 29, as pointed out, these circumferential corrugations give to diaphragms 29 increased radial length which assists in reducing fatigue resulting from circumferential distortion.

Since the construction illustrated in the foregoing is purely an example of one method of producing my invention and the arrangement illustrated is obviously capable of considerable modification, I do not wish to be understood as limiting myself thereto, except as hereinafter claimed.

I claim:

1. In an adjustably bladed rotor adapted to operate in a fluid medium, a hollow hub, blades having shanks mounted for oscillation in bearings in said hub, elastic diaphragms surrounding said shanks, said diaphragms being sealed at their peripheries to said hub and blade shanks, positioning means for said blades including a solid shaft extending into said hub, means effecting a fluidtight seal between said positioning shaft and hub, operating connections between said positioning means and blade shanks within said hub, a fluid lubricant in said hub, said hub including an interiorly disposed expandible chamber the interior of which is in communication with the exterior of the hub in a zone of average pressure.

2. In an adjustably bladed rotor adapted to operate in a fluid medium, a hollow hub, a rotor shaft mounting said hub, blades having shanks mounted for oscillation in bearings in said hub, elastic diaphragms surrounding said shanks, said diaphragms being sealed at their peripheries to said hub and blade shanks, positioning means for said blades including a solid shaft extending through said rotor shaft and into said hub, means effecting a fluidtight seal between said positioning shaft and hub, operating connections between said positioning means and blade shanks within said hub, a fluid lubricant in said hub and said

hub including an interiorly disposed expandible chamber the interior of which is in communication with the exterior of the hub in a zone of average pressure.

3. In an adjustably bladed rotor adapted to operate in a fluid medium, a hollow hub, blades having shanks mounted for oscillation in bearings in said hub, elastic diaphragms surrounding said shanks, said diaphragms being sealed at their peripheries to said hub and blade shanks, positioning means for said blades including a solid shaft extending into said hub, means effecting a fluidtight seal between said positioning shaft and hub, operating connections between said positioning means and blade shanks within said hub, a fluid lubricant in said hub, said hub including an interiorly disposed expandible chamber the interior of which is in communication with the exterior of the hub in a zone of average pressure, the first named diaphragms being provided with circumferentially extending corrugations.

4. In an adjustably bladed rotor adapted to operate in a fluid medium, a hollow hub, a rotor shaft mounting said hub, blades having shanks mounted for oscillation in bearings in said hub, elastic diaphragms surrounding said shanks, said diaphragms being sealed at their peripheries to said hub and blade shanks, positioning means for said blades including a single shaft extending through said rotor shaft and into said hub, means effecting a fluidtight seal between said positioning shaft and hub, operating connections between said positioning means and blade shanks within said hub, a fluid lubricant in said hub and said hub including an interiorly disposed expandible chamber the interior of which is in communication with the exterior of the hub in a zone of average pressure, the first named diaphragms being provided with circumferentially extending corrugations.

5. In an adjustably bladed rotor adapted to operate in a fluid medium, a hollow hub, a hollow shaft mounting said hub, blades having shanks mounted for oscillation in bearings in said hub, a reciprocating shaft extending through said hollow shaft and connected to the blade shanks to oscillate the same, sealing means between said blade shanks and hub and between said shaft and hub whereby to form the hub as a sealed lubricant receiving chamber, and an expandible chamber having a movable wall within the hub and having its interior in communication with the exterior of the hub.
